UNITED STATES PATENT OFFICE.

CHARLES LAWRENCE, OF GREENWOOD, AND GEORGE F. JUBINVILLE, OF HILLESGROVE,
RHODE ISLAND.

CLEANING SLIDE FOR THREAD BOARDS.

Application filed April 3, 1923. Serial No. 629,679.

To all whom it may concern:

Be it known that we, CHARLES LAWRENCE and GEORGE F. JUBINVILLE, citizens of the United States, residing at Greenwood and 5 Hillesgrove, respectively, in the county of Kent and State of Rhode Island, have invented certain new and useful Improvements in Cleaning Slides for Thread Boards, of which the following is a specification.

This invention relates to a cleaning slide used more particularly on the thread-board of a spinning machine and the like; and the object of the invention is to provide such a cleaning slide having a body 10 portion comprising a block with broad, felt-covered bearing surfaces at either end, and having an intermediate recessed portion located between these bearing surfaces. In this recessed portion is mounted carding 15 cloth for the purpose of collecting and rolling up the fly or waste deposited on the thread-board, from the running threads, and also providing a metal guard plate 20 adapted to extend over the edge of the thread-board to prevent the accumulated 25 waste from being engaged and taken up by the rapidly running thread.

With these and other objects in view, the invention consists of certain novel features 30 of construction, as will be more fully described, and particularly pointed out in the appended claims.

In the accompanying drawings:

Figure 1 is a perspective view showing 35 the under side of my improved cleaning block or device.

Figure 2 is a longitudinal section on line 2—2 of Figure 1, looking in the direction of the arrows.

Figure 3 is a transverse section on line 40 3—3 of Figure 1, showing the wire ends of the carding cloth as set in proximity to the bearing surfaces of the block or slide.

Figure 4 is a side elevation showing a 45 portion of the spinning machine with my improved cleaning slide mounted on the thread-board thereon.

Figure 5 is a perspective view of my improved cleaning block mounted on the 50 thread-board of the machine.

It is found in the practical operation of a spinning machine and the like that waste in the form of lint or fly from the running threads, collects upon the thread-board of 55 the machine, which in time works around

into engagement with, and is taken up by the running threads, thereby making knots and bunches on the yarn and injuring its quality. To obviate this difficulty, we have provided a cleaning slide or block of our 60 improved construction, which is adapted to be moved along the thread-board by the hand of the operator, to bunch up and collect the waste or fly on the thread-board and so prevent it from coming in contact with 65 and injuring the yarn; and the following is a detailed description of one construction of our improved cleaner slide by which the cleaning of the thread-board as above described, is accomplished.

With reference to the drawings, 10 designates the body portion of our improved slide member which is preferably formed of a block of wood, the same being recessed near its center as at 11 on its under side 70 leaving broad bearing surfaces 12 and 13 near its opposite ends. Each of these broad bearing-surfaces is covered with felt as at 14, for the purpose of engaging the loose fly or waste which has been deposited 75 on the thread-board and rolling the same into bunches and conducting it back into the receiving space 11 between the surfaces 12 and 13. In this recessed portion 11, we have mounted carding cloth 15, the ends of 80 the wire teeth of which are set to extend down in proximity to the surface of the running board nearly in alignment with the bearing surfaces 12 and 13 of the block, whereby when the waste is rolled by the surface 12 of the block as it is passed along the thread-board it is engaged and collected by 85 these teeth 16 to be further rolled and retained until finally removed when the block is lifted from the thread-board after 90 having made a passage along its surface.

In many instances thread-boards are provided with end members which are hinged to the main board 17, which end members carry the thread guide members 18, and in 100 order that these hinges may not interfere with the operation of the cleaning slide, we have grooved the bearing portions thereof as at 19. In still other cases where the main thread board 17 is hinged to the frame 105 of the machine as at 20, we cut away the rear portion of the slide as at 21 so as not to interfere with this second set of hinges.

In order to positively prevent the 110 accumulated waste on the cleaning slide from

coming in contact with and being picked up by the running thread, we have provided a shield plate 22 which is secured to the outer edge of the cleaning block to extend 5 down over the ends of the hinged members 16 of the thread-board, to ride on the shank portions of the thread guides 11 and so positively prevent the waste from working along these guides to be finally taken up by the 10 threads.

Our improved cleaning slide or block is extremely simple and practical in construction and effective in its operation and by sliding the same along the thread-board of 15 a spinning machine and the like, it will take up and retain the accumulated waste and positively prevent the same from coming in contact with and injuring the running threads.

20 The foregoing description is directed solely towards the construction illustrated, but we desire it to be understood that we reserve the privilege of resorting to all the mechanical changes to which the device is 25 susceptible, the invention being defined and limited only by the terms of the appended claims.

We claim:

1. A cleaning slide for a thread-board, 30 comprising a block presenting wide bearing surfaces at either end and provided with an intermediate recessed portion, a strip of felt covering said bearing surfaces, carding

35 cloth mounted in said recess, and a metal guard to prevent the fly from coming in contact with the running threads, the bearing surfaces and carding cloth being suitably longitudinally recessed to permit the passage of the slide over the upstanding hinges attached to the thread-board.

40 2. A cleaning slide for a thread-board, comprising a block presenting wide bearing surfaces at either end and provided with an intermediate recessed portion, felt covering said bearing surfaces, carding cloth mounted 45 in said recess, the ends of the teeth of said carding cloth and the bearing surface of the block being substantially in the same plane.

49 3. A cleaning slide for a thread-board, 50 comprising a block presenting wide bearing surfaces at either end and provided with an intermediate recessed portion, a strip of felt covering said surfaces, carding cloth mounted 55 in said recess, the ends of the teeth of said carding cloth being set substantially flush with the entire bearing surfaces of the block, and a metal guard having its edge extending over the edge of the thread-board to ride on the thread guide members to prevent waste from being taken up by the running threads.

59 In testimony whereof we affix our signatures.

CHARLES LAWRENCE.
GEORGE F. JUBINVILLE.
